CLAIM

The ornamental design for a product dispenser, as shown and described.

DESCRIPTION

FIG. 1 is a perspective view of a product dispenser showing my new design, shown in a preferred environment for ease of illustration;

FIG. 2 is a perspective view of the product dispenser;

FIG. 3 is an enlarged front view thereof;

FIG. 4 is an enlarged rear view thereof;

FIG. 5 is an enlarged top bottom view thereof;

FIG. 6 is an enlarged bottom view thereof;

FIG. 7 is a left side view thereof;

FIG. 8 is a right side view thereof;

FIG. 9 is a partial bottom perspective view thereof, wherein a portion of the cover is in an open position; and,

FIG. 10 is a reduced top perspective view thereof, wherein a portion of the cover is in an open position.
